VACUUM DISTILLATION APPARATUS

Kenneth C. D. Hickman and Edmond S. Perry,
Rochester, N. Y., assignors to Distillation Products, Inc., Rochester, N. Y., a corporation of Delaware

Application September 12, 1944, Serial No. 553,688

9 Claims. (Cl. 202—205)

1

This invention relates to improved vacuum distillation apparatus particularly of the type wherein the vaporizing and condensing surfaces are stationary and separated by substantially unobstructed space.

High-vacuum unobstructed path distillation apparatus with stationary vaporizing and condensing surfaces is well known. Such apparatus has the definite disadvantage that distilland cannot be distributed on the vaporizing surface in a sufficiently thin film. The distribution takes place by gravitational flow and this limiting factor results in films of relatively great thickness. Since distillation takes place from the surface of the film only such thick films give poor distillation and considerable thermal decomposition. It has been proposed previously that the distilland be distributed on the vaporizing surface by centrifugal force. This represented a distinct advance in the art. However, construction of large rotating vaporizing surfaces is not a simple problem. The gravitational flow type of still heretofore used has had the distinct advantage of simplicity and low cost of construction.

This invention has for its object to provide a vacuum unobstructed path still having a stationary vaporizing surface which is simple and economical to construct, and which enables distribution of distilland thereon in a film substantially thinner than obtained by gravitational flow. Another object is to provide vacuum unobstructed path distillation apparatus in which the surface of the distilling film is rapidly renewed. A further object is to provide improved vacuum unobstructed path distillation apparatus. Other objects will appear hereinafter.

These and other objects are accomplished by my invention which includes vacuum distillation apparatus provided with a stationary vaporizing surface, a condensing surface separated therefrom by substantially unobstructed space and means, which offer relatively little resistance to the flow of vapors, for distributing and rapidly renewing the film of distilland, which means is positioned between the vaporizing and condensing surfaces.

In the following description we have set forth several of the preferred embodiments of our invention but it is to be understood that these are given by way of illustration and not in limitation thereof.

In the accompanying drawing we have illustrated a preferred embodiment of our invention wherein:

Fig. 1 is a vertical section of a still provided

2

with means for distributing distilland on the stationary vaporizing surface:

Fig. 2 is a horizontal section taken on line 2—2 of Fig. 1, and

Fig. 3 is a vertical section of a slight modification illustrating the use of distributing means to offer even less resistance to the flow of vapors than that shown in Fig. 1.

Referring to Fig. 1, numeral 6 designates a cylinder casing provided with an annular recess gutter 8 in the lower and 10 in the upper wall thereof. Numeral 12 designates an integral base and numeral 14 a removable cover which makes a gas-tight connection by means of a gasket 16. Numerals 18 and 20 designate withdrawal conduits for removal of gases from the distillation chamber. These conduits are connected to evacuating pumps (not shown).

Numerical 22 designates a shaft housed in a packed bearing 24. This shaft terminates in an eight-spoked spider 26 and is provided at its lower extremity with a hole 28. Numeral 30 designates a bearing positioned near the center of base plate 12 in which is housed shaft 32. The upper portion of shaft 32 is integral with an eight-spoked spider 34 similar to 26. Spiders 26 and 34 are connected by means of rods 36 to form a single integral rotating element including shaft 22, spider 26, rods 36, brushes 38, spider 34 and shaft 32 as one integral unit. Rods 36 carry numerous wire bristles 38 which are sufficiently long to impinge upon the inside wall of still casing 6.

Numerical 40 designates a cylinder positioned inside the still casing 6 and approximately coaxial therewith. Cylinder 40 is provided with a double wall forming a tight jacket through which cooling fluid is circulated by introduction through conduit 42 and withdrawal through conduit 44. Shaft 46 is integral with the base plate 48 of cylinder 40 and with plate 12 in the still and serves to rigidly maintain cylinder 40 in the position illustrated. Numeral 50 designates a short shaft which protrudes into hole 28 and which is integral with plate 52 of the upper part of cylinder 40, and serves as a means for stabilizing cylinder 40 and maintaining it in the position illustrated. Numeral 54 indicates an annular gutter integral with the base of cylinder 40 but which is connected to withdrawal conduit 56. Numeral 58 designates a conduit connected to the inside middle portion of casing 6 and numeral 60 designates a conduit connected to gutter 8 and numeral 62 designates a conduit connected to gutter 10. Numeral 64 designates a pulley integral with shaft 22. Numeral 66 designates an insulating jacket

55 22. Numeral 66 designates an insulating jacket

surrounding casing 6 in which is positioned a heating element 68.

In operating the apparatus illustrated in Figs. 1 and 2 the system is evacuated through conduits 18 and 20. Heating element 68 is put into operation to heat the wall of 6 to distillation temperature. Force is applied to pulley 64 to rotate the brushes 38 and to cause them to pass over the inside wall of 6. Cooling fluid is introduced into condensing cylinder 40 and distilland is introduced through conduit 58 onto the inside wall of 8. This distilland is immediately spread by the brushes 38 upon the wall of 6 in a thin film which is rapidly renewed due to repeated wiping action of the bristles. The distilland is thus spread over the entire wall of 6 and this spreading action causes at least part of the distilland to travel upward against gravitational force and to pass into gutter 10. Similarly, by a combination of the spreading action and gravitational force the remainder of the distilland, or rather the undistilled residue, passes into gutter 8.

During passage over the inside wall of 6 the film is heated to distillation temperature. Vapors which are generated pass to the condensing surface 40 with relatively little obstruction. These vapors are then condensed to flow by gravity into gutter 43 and are withdrawn from the still through conduit 56. Undistilled residue is withdrawn through conduits 60 and 62.

The construction and operation of the apparatus illustrated in Fig. 3 is very similar to that illustrated and described in connection with Figs. 1 and 2, the only difference being that two brushes 69 only are used and these are mounted on a two-spoked support 70. These brushes offer even less obstruction to the flow of vapors than the construction illustrated in Figs. 1 and 2.

It is apparent that many modifications can be made in the apparatus illustrated without departing from the spirit or scope of our invention. Obviously the number of brushes 38 can be increased or decreased and obviously the rate of rotation can be varied to offset any change in the number of brushes, or to increase or decrease the spreading or filming action. Instead of heating by means of a hot coil as illustrated, it may be preferred in many cases to circulate hot combustion gases in the space between jacket 66 and the outside wall of casing 6. This would be a distinct advantage in that cheap sources of heat could be used. While a brush constitutes the preferred form of distributing and renewing the surface of the distilland, this can be accomplished by other means such as wiper blades having sufficient tension as applied to the inside surface of 6 to spread the distilland in the desired thickness. The bristles etc., should touch the vaporizing surface so that they wipe or smear the distilland into a thin film.

What we claim is:

1. Vacuum distillation apparatus comprising in combination a stationary vaporizing surface, a condensing surface, said surfaces being separated from each other by substantially unobstructed space, means positioned between the vaporizing and condensing surfaces for mechanically distributing distilland onto the stationary vaporizing surface in the form of a thin film and for rapidly agitating and renewing said thin film by mechanical action which means offers relatively little resistance to the flow of vapors from the vaporizing to the condensing surface, means for heating the vaporizing surface, means for cooling the condensing surface, means for introducing distilland

onto the vaporizing surface, means for removing undistilled residue from the vaporizing surface, means for removing distillate from the condensing surface and means for maintaining a vacuum in the space between the vaporizing and condensing surfaces.

2. Vacuum distillation apparatus comprising in combination two hollow, stationary, approximately co-axial members one member serving as a vaporizing surface and the other serving as a condensing surface, said members being separated from each other by substantially unobstructed space, means for mechanically distributing distilland onto the stationary vaporizing surface in the form of a thin film and for rapidly agitating and renewing said thin film by mechanical action, which means offers relatively little resistance to the flow of vapors from the vaporizing to the condensing surface, means for heating the vaporizing surface, means for cooling the condensing surface, means for removing undistilled residue from the vaporizing surface, means for removing distillate from the condensing surface and means for maintaining a vacuum in the space between the vaporizing and condensing surfaces.

3. Vacuum distillation apparatus comprising in combination two hollow, stationary, approximately co-axial members having substantially parallel sides one member serving as a vaporizing surface and the other serving as a condensing surface, said members being separated from each other by substantially unobstructed space, a movable brush adapted to pass over the vaporizing surface distributing and renewing the film of distilland thereon during such passage, said brush offering relatively little resistance to the flow of vapors from the vaporizing to the condensing surface, means for heating the vaporizing surface, means for cooling the condensing surface, means for introducing distilland onto the vaporizing surface, means for removing undistilled residue from the vaporizing surface, means for removing distillate from the condensing surface and means for maintaining a vacuum in the space between the vaporizing and condensing surfaces.

4. Vacuum distillation apparatus comprising in combination two hollow stationary approximately co-axial members having substantially parallel sides, one member serving as a vaporizing surface, and the other serving as a condensing surface said members being separated from each other by substantially unobstructed space, a rotatable brush which offers relatively little resistance to the flow of vapors between the vaporizing and condensing surfaces positioned so that during rotation the bristles thereof pass over the vaporizing surface and distribute distilland thereover in a thin, rapidly renewed film, means for heating the vaporizing surface, means for cooling the condensing surface, means for introducing distilland onto the vaporizing surface, means for removing undistilled residue from the vaporizing surface, means for removing distillate from the condensing surface, and means for maintaining a vacuum in the space between the vaporizing and condensing surfaces.

5. Vacuum distillation apparatus comprising in combination a stationary vaporizing surface, a condensing surface positioned substantially opposite to and separated from the vaporizing surface by substantially unobstructed space, a rotatable brush which offers relatively little resistance to the flow of vapors between the vaporizing and condensing surfaces positioned so that, during rotation, the bristles thereof pass over

the vaporizing surface and distribute distilland thereover in a thin, rapidly renewed film, means for heating the vaporizing surface, means for cooling the condensing surface, means for introducing distilland onto the vaporizing surface, means for removing undistilled residue from the vaporizing surface, means for removing distillate from the condensing surface, and means for maintaining a vacuum in the space between the vaporizing and condensing surfaces.

6. Vacuum distillation apparatus comprising in combination stationary vaporizing and condensing surfaces separated by substantially unobstructed space, which surfaces are approximately circular in cross section and co-axial with respect to each other, a rotatable brush which offers relatively little resistance to the flow of vapors positioned between said vaporizing and condensing surfaces so that it rotates on approximately the same axis as the vaporizing and condensing surfaces, and so that the bristles thereof during rotation pass over the vaporizing surface and distribute distilland thereover in a thin, rapidly renewed film, means for introducing distilland onto the vaporizing surface, means for removing undistilled residue from the vaporizing surface, means for heating the vaporizing surface, means for cooling the condensing surface, means for removing distillate from the condensing surface, and means for maintaining a vacuum between the vaporizing and condensing surfaces.

7. Vacuum distillation apparatus comprising in combination stationary, approximately concentric, cylindrical vaporizing and condensing surfaces, separated from each other by substantially unobstructed space which offers relatively little resistance to the flow of vapors between the vaporizing and condensing surfaces positioned so that, during rotation, the bristles thereof pass over the vaporizing surface and distribute distilland thereover in a thin, rapidly renewed film, means for heating the vaporizing surface, means for introducing distilland onto the vaporizing surface, means for removing undistilled residue from the vaporizing surfaces, means for cooling the condensing surface, means for removing distillate from the condensing surface, and means for

maintaining a vacuum between the vaporizing and condensing surfaces.

8. Vacuum distillation apparatus comprising in combination a stationary, approximately cylindrical vaporizing surface, a stationary approximately cylindrical condensing surface of substantially smaller diameter than the vaporizing surface and positioned inside thereof and approximately co-axial therewith, a rotatable brush which offers relatively little resistance to the flow of vapors between the vaporizing and condensing surfaces positioned so that during rotation the bristles thereof pass over the vaporizing surface and distribute distilland thereover in a thin, rapidly renewed film, means for heating the vaporizing surface, means for introducing distilland onto the vaporizing surface, means for removing undistilled residue from the vaporizing surface, means for cooling the condensing surface, means for removing distillate from the condensing surface and means for maintaining a high vacuum in the space between the vaporizing and condensing surfaces.

9. Vacuum distillation apparatus comprising in combination an approximately cylindrical vaporizing surface, means for bringing hot combustion gases into contact with the outside of said cylindrical vaporizing surface, a substantially cylindrical condensing surface of considerably smaller diameter than the vaporizing surface positioned inside the vaporizing surface and approximately co-axial therewith, a rotatable brush which offers relatively little resistance to the flow of vapors between the vaporizing and condensing surfaces positioned so that during rotation the bristles thereof pass over the vaporizing surface and distribute distilland thereover in a thin, rapidly renewed film, means for introducing distilland onto the vaporizing surface, means for removing undistilled residue from the vaporizing surface, means for cooling the condensing surface, means for removing distillate from the condensing surface, and means for maintaining a vacuum in the space between the vaporizing and condensing surfaces.
